UNITED STATES PATENT OFFICE.

FRANK F. COGGIN, OF MATAWAN, NEW JERSEY, ASSIGNOR TO THE ECONOMY CAR HEATING COMPANY, OF NEW YORK, N. Y., A CORPORATION OF MAINE.

MECHANISM FOR CONTROLLING THE FLOW OF EXHAUST-STEAM.

1,062,080.

Specification of Letters Patent.

Patented May 20, 1913.

Application filed November 15, 1910. Serial No. 592,492.

To all whom it may concern:

Be it known that I, FRANK F. COGGIN, a citizen of the United States, residing at Matawan, in the county of Monmouth and 5 State of New Jersey, have invented new and useful Improvements in Mechanism for Controlling the Flow of Exhaust-Steam, of which the following is a specification.

This invention relates to mechanism for 10 controlling the flow of exhaust steam and is in the nature of an improvement upon the construction covered in my prior Patent No. 1,042,398, of October 29, 1912.

The patent above noted relates to a device 15 for controlling the flow of exhaust steam from a reciprocating engine, such as the air pump on the locomotive, to a heating or other storage reservoir and comprises a differential piston device having one 20 head subject to the opposing pressures of the reservoir and the exhaust from the engine, the other head being exposed on one side to atmospheric pressure. During the 25 first portion of the pump stroke, when the exhaust steam pressure is high, the piston device is held in a position opening communication to the reservoir, but near the end of the stroke, the exhaust steam pressure falls sufficiently to permit the reservoir 30 pressure to shift the piston device to a position in which the usual stack exhaust is opened and the communication to the reservoir is closed. While this apparatus has been found to operate very satisfactorily, 35 there is a possibility of injuring the piston valve device or the buffer spring which acts to take up the shock of the moving piston, due to the impact caused by the sudden movement of the piston device.

40 The principal object of the present invention is to obviate the above difficulty, and for this purpose, I provide means for automatically cutting off the supply of fluid which acts as the propelling force for 45 the piston upon partial movement of the piston, so that a more gradual movement is secured and thereby the impact of the parts is reduced, thus obviating any tendency to breakage.

50 In the accompanying drawing, the single figure is a sectional view of a device for controlling the exhaust steam from an

engine and embodying one form of my improvement.

My improvement is shown in the drawing 55 as applied to a construction similar to that covered in my prior patent hereinbefore referred to, comprising a casing 4 having a piston chamber 3 containing head 5 of a differential piston device and a piston chamber 7 containing the other head 6 of said differential piston. The chamber at one side of piston head 5 is in open communication with steam exhaust pipe 1 of the engine 2 and in one position of the differential 60 piston the head 5 opens communication from the exhaust pipe 1 through ports 8 to a pipe 9 which leads to a steam heating or other storage reservoir 10. In the opposite position of the differential piston, the head 6 65 opens communication from the exhaust pipe 1 through ports 11 to the usual exhaust outlet pipe 12, the head 5 then closing communication from pipe 1 to pipe 9. Adjacent the outer face of piston head 6 which 70 is subject to atmospheric pressure, is a movable buffer plate 16, the movement of which 75 is resisted by a buffer spring 18. A stop device 36 limits the movement of said buffer plate 16.

80 A pipe 13, leading from the reservoir 10 and containing a cut-out cock 15, supplies fluid to a passage 14 in casing 4 and a valve device 37 controls communication from passage 14 to the chamber at the outer face 85 of piston head 5. The valve device 37 is provided with an operating stem which is adapted to engage with the piston head 5, so that the movement of said head to its position opening the ports 8 also pushes the 90 valve device 37 off its seat and establishes communication from the passage 14 through the annular space 38 and ports 39 to the chamber below the piston head 5. The valve device may be provided with a spring 40 95 tending to seat same, and the buffer spring 19 acts as a cushion in the downward movement of the piston.

100 In the drawing, the parts are shown in the position assumed when there is no fluid pressure acting and the piston merely rests upon the buffer spring 19. If the engine is operating, the exhaust steam flows through pipe 1 to chamber 3 and acts on the piston

head 5 to move the piston device to its extreme position in which the buffer spring 19 is compressed and the ports 8 are fully open to the chamber 3 and the flow of exhaust steam, while the smaller piston head 6 closes the ports 11. In this position of the parts, the valve device 37 is pushed off its seat by the movement of the piston head 5 so that communication is open from pipe 13 and the heating reservoir 10 to the outer face of piston head 5.

During the first part of the engine stroke, the exhaust pressure acting on piston 5 is at its highest point and holds the piston in its extreme position, while the exhaust steam flows through ports 8 into the reservoir 10, and equalizes through pipe 13 into the chamber below the piston head 5. As the exhaust pressure diminishes during the latter part of the engine stroke, the pressure below piston 5, aided by spring 19 and the small piston 6 being exposed to atmospheric pressure, soon rises to a point sufficient to start the differential piston valve device upward to close the ports 8 and open outlet ports 11 to the atmosphere, thereby entirely relieving the engine from the back pressure of the reservoir during the latter part of the stroke of the engine piston. During this upward movement of piston 5, the valve 37 is permitted to close as soon as the piston has moved a slight distance to the position shown in the drawing, thereby cutting off further supply of fluid under pressure from the reservoir to the lower side of the piston. It will thus be evident that with the supply of fluid cut off the sudden movement of the piston is prevented, while there is sufficient force due to the expansion of the fluid sealed in the chamber below the piston to effect the full upward movement thereof. The piston device is thus prevented from making violent impact with the buffer plate 16 and danger of breakage of parts is avoided.

I do not wish to be limited to the particular means shown for automatically regulating the supply of fluid to the piston head 5, as it will be evident that various other devices within the scope of the invention may be employed.

For the purpose of cutting the differential piston valve device out of operation whenever desired, there may be provided a cylinder 21 containing a piston 20 having a boss 32 for engaging a stem 22, which passes through a gland or stuffing box 23, and is adapted to engage the piston 5 and raise the same to its upper position with the exhaust outlet ports 11 full open. The supply of fluid from a reservoir 29 for actuating the piston 20 may be controlled by a cock 25, located in the pipe 24, and having ports 26, 27 and 28. When the cock is turned to admit fluid from the reservoir

29 to the cylinder 21, the piston 20 is forced upward, and the flange 30 engages a seat 31 for maintaining a tight joint, and preventing leakage around the piston.

Having now described my invention, what I claim as new and desire to secure by Letters Patent, is:—

1. In an exhaust steam apparatus, the combination with a source of exhaust steam having two outlet passages, and a steam receptacle or reservoir, said passages communicating respectively with the normal exhaust outlet and with said receptacle, of a piston device for controlling said passages and exposed on one side to the pressure of exhaust steam from said source tending to operate said device to close the passage to the normal exhaust, means serving to permit communication from the receptacle to the opposite side of said piston, and means governed by the movement of said piston device for controlling communication from the reservoir to the last mentioned side of said piston device.

2. In an exhaust steam apparatus, the combination with a source of exhaust steam having two outlet passages, and a reservoir, said passages communicating respectively with the normal exhaust outlet and with said reservoir, of a piston device for controlling said passages and exposed on one side to the pressure of exhaust steam, means of communication from the reservoir to the opposite side of said piston device, and a valve governed by the movement of the piston for controlling said communication.

3. In an exhaust steam apparatus, the combination with a source of exhaust steam having two outlet passages, and a steam receptacle or reservoir, said passages communicating respectively with the normal exhaust outlet and with said receptacle, of a piston device for controlling said passages and exposed on one side to the pressure of exhaust steam, means of communication from the receptacle to the opposite side of said piston device when the device is in an extreme position, and means operating to cut off communication from the receptacle to said opposite side of the piston as the same moves from said extreme position to its opposite position.

4. A steam controlling device comprising a casing having an inlet passage, a normal exhaust outlet, and another outlet for diverting a portion of the steam, a piston device for controlling the normal exhaust outlet and exposed on one side to the inlet steam pressure, said casing also having a return passage for admitting the diverted steam to the space at the opposite side of the piston, and means governed by the movement of the piston for controlling communication through said return passage.

5. In a steam controlling apparatus, the

combination with a casing and a piston therein forming a chamber on each side of the piston, of a reservoir, said casing having an inlet passage communicating with one of 5 said chambers, a normal exhaust outlet, and another outlet passage leading to the reservoir, a return conduit from the reservoir to the chamber at the other side of the piston, and means governed by the movement of the 10 piston for controlling the normal exhaust outlet and also the return conduit.

6. The combination with a reservoir, of a steam controlling device comprising a casing having an inlet passage, a normal exhaust outlet and another outlet communicating with the reservoir, a piston device 15 operated by the opposing pressures of the inlet supply and of the reservoir and subjected in one side to the inlet steam pressure, 20 a return conduit from the reservoir to the space at the other side of the piston, and

means governed by the movement of the piston for opening and closing said return conduit.

7. The combination with a reservoir, of a steam controlling device comprising a casing having an inlet passage, a normal exhaust outlet and another outlet communicating with the reservoir, a piston device subject 25 on one side to the inlet steam pressure and operating to control said outlets, a return conduit from the reservoir to the space at the opposite side of the piston, and means governed by the movement of the piston for opening and closing said return conduit. 30 35

In testimony whereof I have hereunto set my hand.
